(57) **CLAIM**

The ornamental design for a strap, as shown and described.

DESCRIPTION

FIG. 1 is a top, front, left perspective view of a strap showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The zig-zag broken lines depict stitching of the strap and form no part of the claimed design. The strap is shown with a symbolic break in its length. The appearance of any portion of the strap between the break lines forms no part of the claimed design. For ease of clarity, the strap shown in FIGS. 4 and 5 is shown without the symbolic break in its length.

1 Claim, 3 Drawing Sheets
